(57) **CLAIM**

The ornamental design for a countertop cashier's station, as shown.

DESCRIPTION

FIG. 1 is a rear isometric view of the design;

FIG. 2 is a front isometric view thereof;

FIG. 3 is a top plan view of the design as shown in FIG. 1;

FIG. 4 is an elevational view of one end of the design;

FIG. 5 is an elevational view of the opposite end of the design;

FIG. 6 is a rear elevational view of the design; and,

FIG. 7 is a front elevational view of the design.

The broken lines shown in the drawing are for illustrative purposes only and form no part of the claimed design.
